US0D1107023S

(12) **United States Design Patent** (10) **Patent No.:** **US D1,107,023 S**
(45) **Date of Patent:** **** Dec. 23, 2025**

(54) **MARKER**

(71) Applicant: **reMarkable A/S**, Oslo (NO)
(72) Inventors: **Anna Karoline Øren Lillerud**, Oslo (NO); **Gaute Wiig Nordby**, Oslo (NO); **Vegard Bakke Svendsen**, Oslo (NO); **Torje Asdahl**, Oslo (NO); **Mats Herding Solberg**, Oslo (NO)

(73) Assignee: **reMarkable AS**, Oslo (NO)

(**) Term: **15 Years**

(21) Appl. No.: **29/928,084**

(22) Filed: **Feb. 8, 2024**

(51) **LOC (15) Cl.** **14-02**

(52) **U.S. Cl.**

USPC **D14/411**

(58) **Field of Classification Search**

(57) **CLAIM**

The ornamental design for a marker, as shown and described.

DESCRIPTION

FIG. 1 is front perspective view of an embodiment of a marker showing its inlay area;

FIG. 2 is a front plan view thereof;

FIG. 3 is a rear view thereof;

FIG. 4 is a tip view thereof;

FIG. 5 is a top (and eraser) view thereof;

FIG. 6 is a left view thereof; and,

FIG. 7 is a right view thereof.

The broken lines in the figures show portions of the marker which form no part of the claimed design.

1 Claim, 4 Drawing Sheets
